Eq. 4

Eq. 5

FIG. 1 is a perspective view of the aerospace craft showing my new design;

FIG. 2 is a top plan view thereof;

FIG. 3 is a bottom plan view thereof;

FIG. 4 is a side elevational view thereof, in the landing position;

FIG. 5 is an elevational view of the opposite side thereof;

FIG. 6 is a front elevational view thereof; and

FIG. 7 is a rear elevational view thereof.

I claim:

The ornamental design for an aerospace craft, as shown and described.
